UNITED STATES PATENT OFFICE.

JOHN F. O. STRATTON, OF SEWICKLEY, PENNSYLVANIA.

FURNACE.

Application filed September 24, 1923. Serial No. 664,376.

To all whom it may concern:

Be it known that I, JOHN F. O. STRATTON, a citizen of the United States, and a resident of Sewickley, in the county of Allegheny and State of Pennsylvania, have invented a new and useful Improvement in Furnaces, of which the following is a specification.

This invention relates to furnaces, and particularly to a furnace adapted to burn crushed or pulverized fuel.

It is an object of the invention to provide a furnace which is simple and sturdy in construction, which will not easily get out of order, which may be readily manipulated, and which is highly efficient in operation.

Special objects are to provide a furnace of the character referred to in which substantially complete combustion takes place, in which the relative proportions of the fuel to the supply of air for combustion may be easily and nicely regulated at will, in which the air supply for combustion purposes is also utilized for cooling the fire pot and grates as well as for cleaning the grates and producing constant agitation of the fuel bed, in which the fuel is agitated and erupted whereby to secure complete combustion and separation of the combustible from the non-combustible portions, and in which the said air supply is preheated before being introduced into intimate contact with the fuel to be burned.

It is also a special object to provide a furnace in which the fire pot proper is fashioned of suitable material and of such form as to readily withstand the high temperatures to which it is subjected, in which the said fire pot is surrounded or encircled by a heat exchange chamber through which the air supply passes, in which the said chamber is constructed in a manner to form a nozzle for directing the air downwardly therefrom and through the spaces between the grate bars for removing any ash or clinkers lodged therebetween, and in which the ash pit serves as a pressure chamber or compartment for storing compressed air to be directed in the form of an upward blast through the fuel in the furnace.

A still further special object is to provide a furnace equipped with a plurality of bodily movable grate sections disposed immediately below and in close proximity to the lower extremity of the fire pot and so positioned relatively to each other as to leave an open space between the sections, to-

gether with means for moving the said grate sections in unison and for selectively adjusting the width of the said open space.

These and other objects of the invention will more fully appear when taken in conjunction with the following description and the appended claims.

In the accompanying drawings, Fig. 1 is a vertical sectional view, with parts in elevation, showing the preferred embodiment of the invention; Fig. 2 a horizontal sectional view taken on the line II—II of Fig. 1; Fig. 3 a similar view taken on the line III—III of Fig. 1; Fig. 4 a fragmentary vertical sectional view taken substantially on the line IV—IV of Figs. 2 and 3; Fig. 5 a detail perspective view showing the construction of one of the grate bars; and Fig. 6 an elevational view of a portion of the actuating mechanism for the grate frames.

The main body of the furnace may conform to any well known construction in respect to the character of material used, and comprises the front wall 1, the bridge wall 2, and the top 3. Located at the lower portion of the furnace and bounded by the walls 4, 5, 6 and 7 is a combined ash pit and air pressure chamber.

The upper portion of the interior of the furnace is lined with any suitable refractory material, preferably in the form of bricks or blocks, such as indicated at 8, while the lower portion thereof, constituting the fire box proper, is constructed of a plurality of sections such as indicated at 9 and 10, the sections 9 forming the side walls of the fire box while the sections 10 form the end walls thereof, the former being inclined so as to converge towards the bottom of the fire pot, and the latter lying in substantially vertical planes. Both the sections 9 and 10 are constructed of cast iron of such character as to be capable of withstanding extremely high temperatures, and all of the sections are corrugated, as clearly shown in the drawings, for the purpose of maintaining all of the parts in intimate contact while at the same time compensating for any variations due to expansion and contraction, all in a well known manner.

As previously noted, the sections 9 are inclined so as to converge towards the bottom of the fire pot, but this convergence preferably stops at a point slightly in advance of the extreme lower extremity of the fire box so as to form a reduced discharge por-

tion 11 having substantially vertical walls throughout its entire extent. This discharge portion is clearly indicated in Fig. 1 of the drawings and projects downwardly within 5 the ash pit and air pressure chamber. Adjacent to and surrounding or encircling the main body of the fire pot is an air chamber 12. This air chamber extends completely around the fire pot and is equipped with an 10 intake conduit 13, all as clearly indicated in Figs. 1 and 3. Projecting within the interior of the chamber 12, and spaced a slight distance from the exterior of the fire pot is a baffle plate 13' conforming in outline to the exterior surface of the pot. The spacing of this baffle in the manner described leaves an open space between the fire pot and the baffle in the nature of a nozzle, the discharge end of which is indicated at 14. 15

20 Although the air chamber and the discharge means for the air therefrom is preferably constructed, as described, it is to be understood that any form of heat exchange chamber provided with means for discharging 25 fluid therefrom downwardly through the grate frames in a manner to be subsequently described in detail is within the contemplated scope of the invention. It is also noted that the lower extremity of the baffle 30 13' terminates slightly above the lower reduced extremity of the fire box so as to permit lateral deflection of the discharged air within certain desirable limits.

Extending transversely through the combined ash pit and air pressure chamber, and located at some distance from the bottom thereof are a plurality of supporting I-beams 15 upon which are mounted a pair of spaced apart tracks 16, 16' each of the 40 tracks being in the form of an inverted T-shaped beam or bar, and these tracks are not only supported upon the I-beams 15 but are held in position by having their opposite extremities embedded in the walls 4 and 5. Mounted for rolling movement upon the tracks 16 and 16' are a plurality of anti-friction members 17, 17'. Each of these 45 anti-friction members consists of a pair of peripherally grooved sheaves 18, 18' attached to the opposite ends of a rod or shaft 19. Cooperating with these anti-friction members and mounted for reciprocating bodily movement thereupon is a pair of track-ways 20, 20' which are in the form of T-bars 50 with the web portions thereof adapted to engage the peripheral grooves of the sheaves 18 and 18'. Attached in any suitable way, as by riveting, to the said track-ways are channel sections 21, the channel sections in 55 turn having fixed thereto in superposed relation one frame of a two-section grate, the said grate frame being indicated generally by the reference numeral 22. The remaining section of the grate is indicated generally at 22', and is constructed similarly to

the section 22 with the exception that instead of being fixedly attached to the track-ways 20, 20', it is mounted for bodily reciprocating rolling movement thereon by means of the supporting wheels 23, the 70 flanges of such wheels embracing the upper portion of the track-ways, in the manner clearly shown in Fig. 4.

The main bodies of each of the grate frames 22 and 22' are of similar construction, consisting of the side bars 24, 24' connected by the end bars 25, 25', and each frame is equipped with a plurality of spaced-apart grate bars 26, extending throughout the entire extent of the frame. The detailed 80 construction of such grate bars is clearly shown in Fig. 5 of the drawing, being somewhat thicker at their upper portions than at their lower portions and being equipped with suitable laterally projecting lugs 17 85 adapted for securing the necessary spacing of the bars, all in an obvious fashion. It is noted that the vertical dimension of the grate bars, corresponds to that of the side and end bars 24, 24', 25 and 25', so that each 90 of the frames 22 and 22' presents a substantially flat upper surface throughout its entire extent.

Each of the frames 22 and 22' is disposed immediately below and in close proximity 95 to the lower extremity 11 of the fire box, and the dimensions of the frames are such that portions thereof extend laterally beyond the fire box at all times so that the downwardly directed blast of air from the nozzle 14 will 100 pass directly therethrough.

Also extending transversely through the combined ash pit and air pressure compartment, and suitably journalled in the walls 6 and 7 is a pair of rock shafts 27, 27'. One end of shaft 27 projects to the exterior of the furnace, and is equipped with a crank arm 28, while similar crank arms 29, 29' are fixed to the said shaft within the compartment. Likewise, the shaft 27' is equipped with the terminal crank arm 30 and the intermediate crank arms 31, 31'. The crank arms 29 and 29' are operatively connected by means of the respective links 32 and 32' to the lower portion of the grate frame 22', the end of the link 32 being pivotally attached to a bifurcated lug 33 depending from the grate frame, while the link 32' is similarly attached thereto at 33'. The crank arms 31 and 31' fixed to the rock shaft 27' are connected respectively to the track-ways 20 and 20' by means of links such as indicated at 34. Pivotally attached to the crank arm 30 and extending therefrom is a link 35 the opposite end of which is pivotally attached as at 36 to the face of a worm wheel 37, the pivotal attachment 36 being in the form of an adjustable nut 110 slidingly mounted in a radial slot 38 pro- 115

vided in the worm wheel so that the pivotal connection may be positioned at a greater or less distance from the center of said worm wheel whereby to vary the 5 rocking movement of the rock shaft 27, and in turn vary the reciprocating movement of the grate frame 22'. In a similar manner, a link 39 is pivotally attached to the crank arm 28, the opposite end of which 10 is fixed to a handle 40 carried by a sector 41 fixed to the link 35 at 42. The handle 40 is pivotally attached to the sector at 43 and may be adjusted to various positions with respect to the sector by means 15 of a bolt 44 attached to the handle and passing through an arcuate slot 45. By this means the handle 40 may be moved to and locked in various angular positions to vary the relative relations of the links 20 35 and 39, and in turn the positions of the rock shafts 27, 27', and the grate frames 22', 22, it being understood that such adjustment effects a moving of the grate frames a greater or less distance apart, 25 according to the direction in which the handle 40 is moved.

The worm wheel 37 is attached to a stub shaft 46 suitably journalled in a bearing 47, and the said wheel is adapted to be 30 driven by means of a worm 48 fixed to a shaft 49 connected to the armature shaft of a suitable motor such as shown at 50. It is noted that all of the driving mechanism, as well as the adjusting means there- 35 for, provided for rocking the shafts 27, 27' is situated upon the exterior of the furnace and may be located at any convenient point.

The top wall 3 of the furnace is suitably 40 equipped with a hopper 51 through which the crushed or pulverized fuel indicated at 52 may be continuously fed in any desirable manner, the details of which have not been illustrated since the same forms no 45 part of the present invention. The front wall 1 is also equipped with a feed opening 53 the outer open end of which is provided with a closure door 54, this feed opening being provided in case it is desirable to inject fuel into the furnace by 50 hand at any time. Likewise, the wall 4 forming the front wall of the ash pit is equipped with the clean-out opening 55 provided with the closure door 56.

In the operation of the furnace, crushed 55 or pulverized fuel 52 is continuously injected through the hopper or chute 51 in the form of a falling stream such as shown at 57, while air is supplied to the air chamber 12 through the inlet conduit 13 in desirable regulated quantities derived from 60 any suitable source such as a blower, compressor, or supply tank.

Upon initially starting the furnace, the 65 fuel may be ignited in any well known fashion such as by the employment of

ignition gas jets or equivalent devices. After the furnace has been properly lighted, the crushed fuel and air is continuously supplied in the manner indicated, the relative proportions of the fuel and air being 70 regulated to obtain substantially complete combustion in a manner to be presently described.

The air admitted to the pressure chamber 12 passes around the baffle plate 13 75 and through the nozzle opening 14 in direct intimate contact with the exterior surface of the fire pot and is directed downwardly in the form of a jet encircling the lower reduced extremity 11 of the fire box. 80 The air blast directed from the nozzle 14 passes downwardly through the openings between the grate bars 26 and dislodges any ash or clinkers which may be lodged between the said bars. During the passage 85 of the air around the fire box and through the grate bars, the same acts as a cooling medium to reduce the temperature of the fire box and the grate frames and renders the air in a pre-heated condition. 90 The air thus discharged passes directly within the entire space forming the combined ash pit and air pressure chamber, 95 previously noted and there absorbs heat from the residue of combustion discharged through the grates and space 58.

Due to the spacing of the grate frames 22 and 22', an opening is left therebetween in the form of a passageway serving as a nozzle through which the compressed air in the 100 ash pit may pass upwardly through the open bottom of the fire box in a manner clearly indicated in Fig. 1, the space between the two grate frames being indicated at 58.

The blast of air passing upwardly through the space 58 is forced through the collected mass of fuel in the lower portion of the fire box resting upon the grate bars, and not only agitates the said fuel mass but effects 105 an eruptive action thereon producing a geyser effect in which the lighter and smaller portions of the fuel are thrown upwardly into the combustive zone of the furnace. The upwardly directed blast of air thus not only functions to disrupt, agitate, and lift 110 the particles of fuel, but is brought into intimate contact therewith under such conditions as to secure the most favorable combustive result.

During such action, the grate frames 22 and 22' are continuously reciprocated back and forth in unison due to their mechanical connection with the rock shafts 27, 27'. Reciprocation of the frames constantly brings 120 the passage 58 below successively new portions of the fuel bed, causing the geyser effect to reach all portions of the fuel bed. In addition to the agitation of the fuel by means of the upwardly directed air blast, of 125 the bodily reciprocation of the grate sections 130

disposed immediately below and in close proximity to the depending discharge end 11 of the fire box keeps the entire fuel bed upon the grates in a mobile condition.

5 It is noted that the finer portions of the powdered fuel are completely ignited and consumed in the upper portion of the combustion zone, and due to the fact that the combustible portions as well as the partially 10 consumed particles thereof are lighter than the non-combustible parts they will be forced into the combustion zone while the non-combustible portions in the form of ash and clinkers will gradually collect in the lower 15 portion of the fire box upon the grate frames to be ultimately ejected therefrom into the ash pit under the influence of the downwardly directed air blast from the nozzle 14. The segregation of the non-combustible portions 20 in the lower portion of the furnace and the transference of the combustible portions thereabove is also enhanced due to the constant agitation of the fuel bed by means of the reciprocation of the frames. It is 25 particularly pointed out that as the partially consumed particles work their way towards the lower portion of the fire box, and become partially volatilized, they are lifted under the influence of the upward air 30 blast, the heavier non-combustible portions again falling downwardly towards the grate bars, this cycle of operations being repeated until the combustible portions have been 35 entirely consumed and the non-combustible portions segregated therefrom and discharged into the ash pit. The inert non-combustible matter being of greater specific gravity than the incandescent partially volatilized matter, such inert matter will fall 40 into the ash pit against the stream of air passing upwardly through the opening 58.

The pressure of the air within the air chamber 12 and within the air pressure compartment may be regulated by any well 45 known means, such as by varying the speed of operation of the blower or by the interpolation of suitable controlling valves. The quantity of air permitted to pass from the air pressure compartment into the furnace, 50 however, is governed by regulating the width of the passage 58 between the grate frames, the width of this passage being governed by the setting of the handle 44. By properly regulating the proportions of the fuel and 55 air admitted, substantially complete combustion of all combustible portions of the fuel may be accomplished.

The fluid admitted through the inlet conduit 13 has been referred to as "air," but it 60 is obvious that any fluid for supporting oxidation of the fuel may be used in the same manner and with a similar result. It is also pointed out that the cooling of the fire box and grate bars, and the cleaning action due 65 to the downward discharge of the fluid from

the nozzle 14, although preferably carried out as described, may be accomplished by any desirable heat exchange medium, and the medium for supporting oxidation may be supplied to the combined ash pit and 70 pressure compartment from an independent source.

It is thus seen that the invention provides a furnace in which crushed or pulverized fuel may be burned with substantially complete combustion, in which the cooling medium for the fire box also acts as a cooling and cleaning means for the grates as well as an agitating medium for the fuel mass upon the grates, in which the air blast for 80 supporting combustion produces an eruptive geyser effect throughout successive portions of the fuel bed, in which the air for supporting combustion is preheated before being brought into intimate contact with the fuel, 85 in which the necessary proportions of air for supporting combustion may be regulated by adjusting the width of the space between the sections of the grate, in which the air for supporting combustion coacts with the 90 bodily reciprocating grates to maintain the fuel mass upon the grate bars in a mobile condition, and in which the actuating and adjusting mechanism for the grates is disposed at a convenient point at the exterior 95 of the furnace.

I claim:

1. A furnace comprising a fire pot having an opening in the bottom thereof, an air pressure compartment therebelow, a bodily movable grate interposed between the said fire pot and compartment, said grate being composed of a plurality of independently movable spaced apart sections, and means for moving said grate sections in unison 100 whereby to vary the position of the space therebetween transversely of the fire pot.

2. A furnace comprising a fire pot having an opening in the bottom thereof, an air pressure compartment therebelow, a bodily movable grate interposed between the said fire pot and compartment, said grate being composed of a plurality of independent sections positioned relatively to each other whereby to leave a space therebetween, 110 means for moving said grate sections in unison, and means for adjusting the width of the space between said sections.

3. A furnace comprising a fire pot having an open bottom, an air pressure compartment therebelow, and a plurality of spaced-apart grate frames interposed between the said bottom and compartment, the space between the said frames serving as a nozzle for directing an air blast of predetermined area upwardly through the fire box, and means for bodily moving the said frames to shift said blast area laterally of the fire pot.

4. A furnace comprising a combined ash

- pit and air pressure compartment, a fire box having an open bottom projecting downwardly through the top of said compartment, a pair of reciprocating grate frames disposed immediately below and in close proximity to the lower extremity of the fire box, a space between the said frames defining a blast nozzle for directing air upwardly through the said space into the fire box, and means for reciprocating the said frames to move the air blast area transversely to and fro beneath the fire box.
5. A furnace comprising a combined ash pit and air pressure compartment, a fire box having an open bottom projecting downwardly through the top of said compartment, a pair of spaced apart reciprocating grate frames disposed immediately below and in close proximity to the lower extremity of the fire box, the space between the said frames serving as a blast nozzle for directing air upwardly through the fire box, means for bodily reciprocating the said frames in unison, and means for adjusting the relative positions of the frames to vary the width of the space therebetween.
6. A furnace comprising a combined ash pit and air pressure compartment, a fire box having an open bottom projecting downwardly through the top of said compartment, an air chamber adjacent the fire box, said chamber being provided with a discharge opening, a bodily movable grate interposed between the said fire box and compartment and projecting beyond the sides of the fire box, the air from the said discharge opening being directed downwardly through the laterally projecting portions of the said grate.
- 40 7. A furnace comprising a combined ash pit and air pressure compartment, a fire box having an open bottom projecting downwardly through the top of said compartment, an air chamber immediately surrounding the fire box and provided with a baffle plate spaced from the exterior of the fire box to provide a downwardly directed nozzle, a pair of spaced apart reciprocating grate frames disposed below the lower extremity of the fire box and projecting laterally therebeyond whereby the air discharged from the said nozzle will pass through the said frames, and means for reciprocating the said frames.
- 55 8. A furnace comprising a combined ash pit and air pressure compartment, a fire box having an open bottom projecting downwardly through the top of said compartment, an air chamber immediately surrounding the fire box and provided with a baffle plate spaced from the exterior of the fire box to provide a downwardly directed nozzle, a pair of spaced apart reciprocating grate frames, disposed below the lower extremity of the fire box and projecting later-
- ally therebeyond whereby the air discharged from the said nozzle will pass through the said frames, means for reciprocating the said frames, and means upon the exterior of the furnace for adjusting the width of the space between the frames.
9. A furnace comprising a combined ash pit and air pressure compartment, a fire box having an open bottom projecting downwardly through the top of said compartment, a bodily movable track-way mounted for reciprocation in the said compartment, a grate frame fixed to the said track-way, a second grate frame supported for bodily reciprocating movement upon the said track-way and spaced from the said first-named grate frame, both said frames being disposed immediately below the fire box, and means for bodily reciprocating both said frames in unison.
10. A furnace comprising a combined ash pit and air pressure compartment, a fire box having an open bottom projecting downwardly through the top of said compartment, a bodily movable track-way mounted for reciprocation in the said compartment, a grate frame fixed to the said track-way, a second grate frame supported for bodily reciprocating movement upon the said track-way and spaced from the said first-named grate frame, both said frames being disposed immediately below the fire box, and means for bodily reciprocating both said frames in unison, said means including means for selectively adjusting the width of the space between the said frames.
11. A furnace comprising a fire pot having an opening in the bottom thereof, an air pressure compartment therebelow, fuel supporting means interposed between the fire pot and the said compartment, said fuel supporting means being composed of independently movable separated sections whereby to provide an upwardly directed blast between the sections, and means for actuating the said sections to move the position of the said blast transversely of the fire pot.
12. In combination in a furnace, a fire pot, means for supporting fuel in said fire pot, means for creating an upwardly directed blast of sufficient force to erupt fuel carried on said fuel supporting means, means for confining said blast to a predetermined area less than the cross-sectional area of the fire pot, and means for moving the last-named means transversely of the fire pot whereby to shift the region of said blast, said blast confining means being constantly positioned below the fire pot.

In testimony whereof, I sign my name.

JOHN F. O. STRATTON.

Witness:

EDWIN O. JOHNS.
